UNITED STATES PATENT OFFICE.

EUSEBE DEMERS, OF SAN FRANCISCO, CALIFORNIA.

DEVICE FOR DRAWING STEAM-BEER.

SPECIFICATION forming part of Letters Patent No. 577,728, dated February 23, 1897.

Application filed May 15, 1896. Serial No. 591,673. (No model.)

To all whom it may concern:

Be it known that I, EUSEBE DEMERS, a citizen of the United States, and a resident of the city and county of San Francisco, State 5 of California, have invented a new and useful Device for Drawing Steam-Beer at Various Degrees of Temperature; and I do hereby declare the following to be a full, clear, and exact description of the invention, such as will 10 enable others skilled in the art to which it app pertains to make and use the same, reference being had to the accompanying drawings, and to the letters of reference marked thereon, which form a part of this specification.

15 My invention relates to improvements in apparatus or devices employed in drawing steam-beer, which, as dealers know, is a fermenting beer exceedingly difficult to draw in a clear state without venting the keg or barrel, 20 wherein it is contained and therefore without depriving it gradually of its natural flavor and strength.

The object of my said invention is to provide an improved apparatus or device by 25 means of which persons retailing this kind of beverage may draw it readily and without trouble from an unvented keg or barrel into a glass or pitcher in the most suitable condition for drinking, that is, neither too foamy 30 nor flat, but quite sharp, and withal at such temperature as will best suit the taste of the consumer.

In the drawings hereto annexed, Figure 1 is a sectional side elevation of my improved 35 device or apparatus aforesaid. Fig. 2 is a similar view of a modification thereof, and Fig. 3 is a longitudinal sectional elevation of a faucet forming part of the construction illustrated at Fig. 1.

40 In carrying out my invention I make use, first, of a pressure-regulator, through which all the beer from the keg or barrel on tap is made to pass. This regulator comprises a conical cylinder or tube A, having its tapering end turned toward the keg, with which it is connected by means of a pipe or conduit a, joined to it by a union-coupling a'. Within this tube is placed a rotary plug a² of corresponding shape and provided with a detachable stem a³, passed through a screw-cap a⁴, and furnished with a screw-handle a⁵. The stem a³ has a screw-threaded portion a⁶,

engaging a suitable screw-thread in the cap a⁴, and serves to move the plug a² lengthwise within the tube A and thereby cause it to obstruct or close more or less the passage therethrough. The plug is made short enough so as not to reach fully to either end of the tube, leaving a small space a⁷ between it and the screw-cap a⁴ and a similar space a⁸ at the opposite end, where it terminates in a neck a⁹, carrying a circular valve a¹⁰, adapted to control the opening a¹¹ into which the pipe a discharges. A short pin a¹², passed through a suitable hole in a bridge a¹³, guides this valve a¹⁰ and the tapering end of the plug in their movements. The valve a¹⁰ is set a little farther away in proportion from the bridge a¹³ than the sides of the plug a² are from the tube A, so that the inlet for the beer may yet be fairly well open when the passage through the tube is nearly closed.

It will now be seen that owing to the arrangement above set forth the pressure of the beer from the keg will be greatly reduced or broken in its passage through the tube A. The keg need not be vented, as is usually done, but the beer therefrom is allowed to flow out in its natural state into the regulator. The flow will first be checked by the valve a¹⁰, which is well adapted in its position on the end of the plug to receive the impact of the incoming beer and break its force before the beer reaches the space a⁸. From the latter point the beer is spread out into a thin film all around the plug in the tube, so that by the time it reaches the space a⁷ under the cap a⁴ it has lost a great deal of its foam-creating power. The regulator being of conical shape deflects the course of the beer and causes it to spread over a gradually-increasing surface as it proceeds on its way, with the result that it gets to the bigger end of the plug in a more liquid state than if it were passing through a straight tube. The rapidity of the flow will of course be regulated by the position of the rotary plug, which is to be screwed or unscrewed according to the pressure or condition of the beer in the keg.

To the regulator is attached a cooler B, 100 which is set in a convenient ice chest, box, or case C, under or in the base of which the regulator is preferably located. This cooler consists of a globular receptacle made of any

approved material, such as brass or tin or other metal, and is screwed to a suitable base *b*, provided with a tubular extension *b'*, passing through the bottom of the chest *C* and secured thereto by an external screw-thread *b²* and a lock-nut *b³*. The regulator is connected with this extension *b'* of the cooler-base by means of a short outlet-pipe *a¹⁴*, formed in its top side and held in place by a union-coupling *a¹⁵*, so as to be in line with a tube *b⁴*, fitted in said extension and leading into the upper part of the cooler. The beer from the regulator reaches the cooler through this tube, which is stopped or covered with a hood *b⁵* at its upper end, but has side holes *b⁶* under said hood to let the beer escape, as indicated by the arrows in Fig. 1. The cooler has at its top an air-cock *b⁷*, which allows the air to be expelled from it when first filled with beer. The hood *b⁵* of the tube *b⁴* being directly under the air-cock prevents the beer from shooting upward into it and further reduces the strength of the flow from the keg, the beer falling in small streams through the holes *b⁶* into the bottom part of the cooler, where it is subjected to the action of the ice contained in the chest.

The beer can be drawn from either the cooler or the regulator, or from both the cooler and regulator at the same time through a faucet *F*, of peculiar construction. The body of this faucet is formed with two passages *f* *f'*, the upper passage *f* terminating rearwardly in a nipple *f²*, screwed through the front part of the ice-chest and into a pipe *b⁸*, extending from the cooler-base *b*, and the lower passage ending under the faucet-body with a similar nipple *f³*, connected by means of a pipe *G* and suitable union-couplings *g* *g'* to an outlet-pipe *a¹⁶*, formed either in one side or in the bottom of the regulator, as shown at Fig. 1. These two passages both lead in the usual way to the barrel or plug-chamber of the faucet, where they are controlled by a rotary hollow plug *f⁴*, having a suitable head *f⁵* and lateral openings *M* *M* *N* *C*, adapted, respectively, to register with both said passages jointly and with either of them separately, according to how the said plug is turned. The two openings *M* are in the same vertical plane and when brought into the position illustrated at Fig. 1 coincide both with the two passages *f* *f'*. The openings *N* and *C*, on the contrary, are in different planes, the opening *N* being adapted to register only with the lower passage *f'*, and the opening *C* with the upper passage *f* alone. All said four openings are located within one-half of the circumference of the hollow plug, the opening *N* being shown in dotted lines only. It will now be seen that if the opening *C* be brought into line with the conduit *f* connected with the cooler the faucet will draw cold beer, that if the opening *N* be made to register instead with the conduit *f'* beer will be had in its natural state from the regulator, and that when the openings *M* are in com-

munication with both said conduits mixed or moderately-cold beer will be drawn.

It is intended to stamp or otherwise impress or mark the words "Cold," "Natural," and "Medium" at suitable points on the head *f⁵* of the plug *f⁴* to indicate the various degrees of temperature at which the beer can be obtained and how to turn the plug to draw the same.

The body of the hollow plug is shaped like a truncated cone, as illustrated, and it is turned to the right or left, as required, by means of a lever-handle *f⁶*, secured in its head *f⁵*. The discharge-passage through the plug *f⁴* is also controlled by an inner solid plug *f⁷*, of conical shape. This inner plug is rotatable like the outer one, and is movable up and down within it by means of a stem *f⁸*, passing upwardly through the head *f⁵* and having a screw-threaded portion *f⁹* fitted therein. The stem *f⁸* projects outwardly from the head *f⁵* and is provided with a screw-handle *f¹⁰*, by means of which it is turned to either raise or lower the inner plug *f⁷* and consequently open or close the discharge-opening through the hollow plug. The plug *f⁷* is used in order to further break or reduce the gas-pressure on the outflowing beer and cause the beer to fall into the glass or pitcher underneath in a bright liquid state, without excess of foam. This plug can be set so as to regulate the flow of beer at the outer end of the faucet to suit and, if desired, may be kept permanently raised within the hollow plug in order to leave the discharge-opening thereof partly open whenever and as long as the apparatus is in use. It will be observed that it is not necessary to hold that plug with the hand in drawing the beer, whether it be permanently raised or not, and if the glass be placed on a stand underneath the beer can be drawn without holding either the glass or plug, as must be done with certain other forms of beer-drawing devices.

In Fig. 2 is represented a modified construction of my invention which may be found preferable to that previously described, where it is desired to serve only cold beer and cheapness of construction is an object. The apparatus there illustrated operates substantially on the same principle as that shown at Fig. 1 except the regulator is placed inside the cooler and the intervening parts are dispensed with. The beer in that case flows directly into the cooler through the upper flaring part of the regulator, which has no screw-cap, the stem *a²* of the plug *a³* passing through a screw-threaded opening *b⁹* in the top of the cooler *B* and projecting above the ice-chest *C*. The air-cock *b⁷* is then placed a little to one side of that top opening. The improved faucet hereinbefore described may be used also with this modified form of my beer-drawing device, if desired, though I prefer to use a plainer faucet *F'*, having but one passage *f* and only one plug *f⁷*, which is made solid and entirely controls the flow through the plug-chamber.

The stem f^8 of this single plug has a screw-threaded portion f^9 , fitted in a head f^{11} , and a screw-handle f^{10} , as in the other construction.

If it were desired to deal out only "Natural" beer instead of "Cold," for instance, after the cooler has been emptied at night, a stop-cock (not shown) could be placed in the upper outlet-pipe a^{14} , Fig. 1, so as to draw beer only from the regulator.

10 Having described my invention, what I claim is—

1. In a beer-dispensing apparatus, a conical casing, a conical plug placed therein but of enough smaller diameter than the casing 15 to allow a space all around for the flow of the liquid through the casing, a valve at one end of the plug to control the supply of fluid, and a screw-rod at the large end of the plug to center and adjust it endwise, combined with 20 a cooler, a pipe extending thereto from the conical casing, a faucet connected to the

cooler, and a pipe G, extending from the conical casing to the faucet which is provided with two passages through it, substantially as described.

25

2. In a faucet, the body having two passages f, f' , through it, and a hollow plug provided with a series of openings through it to communicate with said passages, the plug being provided with a head f^5 , and handle f^6 ; 30 combined with a solid plug f^7 placed inside of the hollow plug, and a screw-rod f^8 for centering and adjusting the solid plug in the hollow one; a space being left between the two plugs to allow a free flow of fluid between them substantially as shown.

In testimony whereof I affix my signature in presence of two witnesses.
